(57) **CLAIM**

The ornamental design for scissors, as shown and described.

DESCRIPTION

FIG. 1 is a front, right and top perspective view of scissors, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG.

2 comprising an adjusting knob; and,

FIG. 10 is an exploded view of the scissors of FIG. 1.

The broken lines shown in the drawings are included for the purpose of illustrating portions of the scissors that form no part of the claimed design.
